United States Patent Office

Des. 224,804
Patented Sept. 19, 1972

224,804

CUP HOLDER

William Harvey Dennerlein, Plainview, and John Duncan Wark, Freeport, N.Y., assignors to American Can Company, Greenwich, Conn.

Filed Feb. 9, 1971, Ser. No. 114,106

Term of patent 14 years

Int. Cl. D7—01

U.S. Cl. D44—9

FIG. 1

FIG. 2

FIG. 3

FIG. 4

FIG. 1 is a side elevational view of a cup holder showing our new design;

FIG. 2 is a top plan view of the cup holder of FIG. 1;

FIG. 3 is a bottom view; and

FIG. 4 is a sectional view taken along line 4—4 of FIG. 2.

We claim:

The ornamental design for a cup holder, as shown.
